UNITED STATES PATENT OFFICE.

THOMAS C. SPELLING, OF NEW YORK, N. Y.

NECKTIE-FASTENER.

1,192,236.

Specification of Letters Patent. Patented July 25, 1916.

Application filed April 24, 1916. Serial No. 93,108.

To all whom it may concern:

Be it known that I, THOMAS C. SPELLING, a citizen of the United States of America, residing at New York city, in the county of 5 New York and State of New York, have invented certain new and useful Improvements in Necktie-Fasteners, of which the following is a specification.

This invention relates to necktie fasteners, 10 and is adaptable to neckties of all varieties; to bow ties manufactured to order and such as are sold in the form of scarfs, to be passed around the collar and tied on as often as worn; as well to ties of the hanger variety 15 permanently made up as to those sold in the form of scarfs to be passed around the collar and tied on as often as worn and known as four-in-hand.

It has for a principal object the provision 20 of a simple flexible lower plate and an overlying plate attached thereto, for impinging and holding the neck of the button and the button head, and detachably connecting them with the tie, by means presently to be 25 described.

Further objects will be apparent from the following specifications, appended claim and drawings.

Referring now to the drawings: Figure 30 1 is a top view of a thin plate slotted and with appendant tongues struck therefrom as there seen, and Fig. 2 is a side view of said plate. Fig. 3 is a view of a plate of identical dimensions having a corresponding and 35 wider slot but no struck out tongues. Fig. 4 is a perspective view of the completed device, Fig. 5 is a view of the side of the device nearest the wearer when it is in place ready for use in connection with a bow tie, and 40 Fig. 6 is a perspective view of the device when used in connection with a tie of the hanger variety. Fig. 7 is a sectional view of the device, and Fig. 8 is a modification.

Referring to the drawings, more in detail, 45 similar reference characters indicating identical parts in the several views, the tongues A are struck from the thin plate, left in attachment at the ends nearest the side thereof at which the slot begins. The tongues are 50 slightly curved from the horizontal intermediate their ends, and the free ends are bent back to the horizontal. The slot B is barely sufficiently wide to admit of the passage therethrough of the neck of the collar 55 button to its resting place at D, while the wider and overlying slot E is barely wide

enough for the passage therethrough of the widest portion of the button head to its resting place at F. The two plates, the thicker (Fig. 3) overlying the thinner (Fig. 1) may 60 be riveted together as at G, or otherwise joined. The thread holes H extending through both plates, and exactly corresponding as to position are for use only for permanent attachment of the device to a bow 65 tie ready made up, while the larger and similarly constructed holes I are for the passage therethrough of tapes, cords or wires for connecting other kinds of ties to the collar button through the instrumentality of 70 the fastener. At J such connection is shown. The utility of such connection is seen by persons skilled in the art to consist in the support in place and preservation of shape thus afforded to the tie. In the illustration just mentioned, the effect is enhanced 75 by the presence of tie-clasp K to which the exterior end of the cord is attached at L. But the connecting cord, tape or wire may be gripped or attached to the tie by any suitable means, such as will readily occur to the mind without specification. These larger 80 holes are disposed in a central and vertical line extending almost the entire length of the plates so that the connection may be 85 made from various points opposite the like central line of the tie to meet variations in their lengths and forms. With the parts in place, the extreme point of the button head extends slightly beyond the outer surface of 90 the upper plate as seen at M.

In use the completed device is pressed 95 against the collar, and simultaneously outward pressure may be applied to the shield, inside the shirt band, whereupon the said resilient tongues yield and the plane of the thinner plate is brought below the button head. Another important office of these 100 tongues is the offsetting of the slight curvature of the collar. Without them, contact might occur only on a point of very limited area and the correct relative position of the fastener might be difficult to preserve.

A movement of the device to the right or left, as the case may be,—it being immaterial 105 whether the slot be made on the right or on the left side,—causes the neck to move along the narrow and the head along the wider slot, and along the groove formed by the relation and position of the two slots until 110 both neck and head have reached their respective rest points. A large portion of the

head then overlaps the lower plate, and rests there as on a shelf, and the coaction of all the parts wedge the portion of the lower plate under said head and hold all the parts 5 in place, the outward pressure being equalized by the resistance of the shield seen at N in Fig. 7.

In use with a ready made bow tie, if the 10 same be permanently attached to the device, the fabric of the tie will yield to allow the protruding portion of the button head to travel along the groove.

The modification (Fig. 8) illustrates a construction of the device from a single piece 15 of material. The embodiment described above in detail is preferred because of the varying dimensions of button heads, there being no such variation in the dimensions of the necks, so that upper plates having 20 slots of varying widths may be provided without corresponding changes in thinner plates, conducing to economy of manufacture. An additional reason for such preference is the superiority in flexibility of the 25 tongues when struck from a thin plate. Fur-

ther modifications may be made in view of the appended claim, no limitation being implied by the drawings, which are submitted for illustrative purposes only.

I claim:

A tie fastener of the class described comprising a relatively thin plate having an offset slot formed therein to receive the shank of a collar button, resilient tongues formed in said plate and bent from the plane 35 thereof to frictionally engage a collar, a supplemental and thicker plate carried by said first mentioned plate having a corresponding offset slot formed therein of a wider measurement to receive the head of 40 a collar button therein, and a plurality of holes formed in said plates to receive fastening means carried by a necktie.

In testimony whereof I affix my signature in presence of two witnesses.

THOMAS C. SPELLING.

Witnesses:

JAMES ROSTHAL,
MOLLIE QUATINETZ.
